CLAIM

The ornamental design for a rearing pot, as shown and described.

DESCRIPTION

FIG. 1 is a front perspective view of a rearing pot, showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown illustrate both parts of the article and boundaries of the claim wherein none of the broken lines form no part of the claimed design.

1 Claim, 7 Drawing Sheets
